F. WRIGHT.

GIRL'S COSTUME.

No. 15,376.

Patented Aug. 26, 1884.

UNITED STATES PATENT OFFICE.

FRANCES WRIGHT, OF NEW YORK, N. Y., ASSIGNOR TO THE BUTTERICK PUBLISHING COMPANY, (LIMITED,) OF SAME PLACE.

DESIGN FOR A GIRL'S COSTUME.

SPECIFICATION forming part of Design No. 15,376, dated August 26, 1884.

Application filed June 23, 1884. Term of patent 3½ years.

To all whom it may concern:

Be it known that I, FRANCES WRIGHT, of the city, county, and State of New York, have invented and produced a new and original 5 Design for a Pattern of a Girl's Costume, (numbered 9,322;) and I do hereby declare that the engraved prints accompanying this specification convey to any one accustomed to using paper patterns a clear understanding of how 10 a garment made up by the pattern will appear.

The design shows a full vest upon the upper part of the front at the center, short jacket fronts flaring widely below the neck, and pointed draperies below the waist-line flaring widely

over the center and displaying draping plaits 15 in their back edges; a half-fitting Princess dress back, exhibiting a large sash-bow at the center just below the waist-line; a standing collar, and coat-sleeves.

What I claim as my invention, and desire 20 to secure by Letters Patent, is--

The design for a girl's costume, as shown in the engraved prints accompanying this specification.

FRANCES WRIGHT.
